DETACHABLE SERVING TRAY

Ernest E. Silkenat, Mission Urban Township,
Johnson County, Kans.

Application May 11, 1959, Serial No. 55,855

Term of patent 14 years

(Cl. D44—10)

Fig. 1 is a front perspective view of a detachable serving tray embodying my new design;

Fig. 2 is a side elevation of same;

Fig. 3 is a rear end elevation of same; and

Fig. 4 is a bottom plan view of same.

I claim:

The ornamental design for a detachable serving tray, as shown.
